UNITED STATES PATENT OFFICE

2,373,538

MULTISERVICE BALLAST CAR

Argyle Campbell, Chicago, Ill., assignor to Enterprise Railway Equipment Company, Chicago, Ill., a corporation of Illinois

Application October 9, 1942, Serial No. 461,415

1 Claim. (Cl. 105—251)

My invention relates to improvements in hopper bottom load discharging cars, and is especially related to a type of hopper car suitable for commercial and for economic track ballasting services.

One of the objects of my invention is to provide a car with a large cubic capacity in proportion to dimensions and weight for hauling revenue producing freight such as coal and for the economic and convenient unloading of such freight by the consignee at destination.

A further object of the invention is to provide a car for the transportation of and the economic placement of ballast upon the railway track.

A further object of the invention is to provide for the placement of ballast from a moving car to the center or two sides of the track, and in place and quantities, small or large as the conditions may require.

The improvements of my invention are applicable to a standard AAR hopper car body except the lower hopper portion thereof, for which has been substituted hoppers and door operating mechanisms of a character commonly used for track ballasting cars. In this combination I have arranged the parts and structure in a new and novel manner which provides a commercial or track ballasting car of relative light weight in proportion to the cubic capacity available for coal, and a track ballasting car of greater efficiency than has been heretofore attained.

Referring to the accompanying drawings which illustrate a car embodying the invention,

Fig. 1 is a view in side elevation of a sufficient portion of the length of the car to illustrate one set of longitudinal hoppers and a portion of the next adjoining set of hoppers;

Fig. 2 is a vertical, longitudinal section of that portion of the car which is illustrated in Fig. 1, which section is on a line substantially midway of the side of the car and the longitudinal center thereof, on approximately the line 2—2 of Fig. 5;

Fig. 3 is a plan view of the underframe of the car showing that portion of the length of the car which is illustrated in Figs. 1 and 2, and more than one-half of the width of the car;

Fig. 4 is a transverse, vertical section taken on the line 4—4 of Fig. 3;

Fig. 5 is a transverse, vertical section taken on the line 5—5 of Fig. 3;

Fig. 6 is a transverse, vertical section taken on the line 6—6 of Fig. 3, showing one of the handles which are located at each side of the car, and the worm gear mechanism inside of the housing at the center of the car for operating a pair of center hopper discharge doors;

Fig. 7 is a detail view of the operating handle and the worm and gear mechanism for operating one of the four side discharge doors of the car;

Fig. 8 is an enlarged detail section of one end of a hopper, this section being taken on substantially the same line 2—2 of Fig. 5 to illustrate the relation of the upper end flange of the car door with the downward extension of the end floors and to illustrate the transverse plates which carry the door hinges and which provide baffles at the ends of the hopper doors;

Fig. 9 is a transverse, vertical section on the line 9—9 of Fig. 3, showing the relation of the center sills of the car, the main operating shaft for the center doors, the door chains for said doors, and the sheave wheels for said chains; and also showing the ballast spreader in relation to the transverse door support and baffle plates;

Fig. 10 is an enlarged sectional view of a car door, the door bracing, the door brace extension, and the guiding and attaching means for the chain; and

Fig. 11 is a bottom plan view of the end portion of the car door showing the door brace extension and chain guiding and attaching means illustrated in Fig. 10.

In the drawings the lower portion of the car body A is shown, having side sills A' and center sills E, between which the longitudinally disposed discharge hoppers are located. The hoppers are disposed in pairs. Each hopper has two doors F which are hinged together an a hinging rod 3 which, as shown more clearly in Fig. 5, is disposed substantially above the rail R of the track so that the inside or center doors of the pair of hoppers will direct the discharging load to the space between the rails and the outside doors will direct the discharging load outside of the rails. Thus, as the car moves along the rails, particularly when the car is used for ballast material, this material can be placed either in between or outside of the rails, as conditions require. The end of each hopper is formed by a sloping end floor sheet B and a sloping cross hopper sheet G at the center of the car.

The side walls of the hoppers are formed by the longitudinally disposed side floor sheets C and the inside sloping hopper sheets D. These hopper walls are placed as low as possible in a car body to add as much increase in car capacity as possible, and in the present car it will be noted that the hoppers are practically within the height of the center sill and in substantially the same level therewith. Below the hoppers are sub-hopper portions which in effect constitute the hopper discharge outlets. These sub-hoppers are formed in general by the doors when closed, and by vertical extensions B' and G', respectively, of the hopper end sheets B and the cross hopper sheets G, as shown more clearly in Figs. 2 and 8, these extensions being V-shaped and forming end walls for the sub-hoppers. These extension walls B' and G' extend downwardly into close proximity

to the inner faces of the doors when closed. In this form they project below the edges of upturned flanges 1 formed at the edges of the doors. These door flanges 1 lie outside of the extension walls B' and G', and closely adjacent thereto, so that when the doors are closed the material in a loaded car cannot pass the ends of the sub-hoppers.

As hereinbefore mentioned, the doors F of each hopper are hinged along their adjoining edges on a hinging rod 3 which extends longitudinally of the car beyond the edges of the doors and has bearings 2 in transverse door supporting and baffle plate members H. These members H, as shown more clearly in Fig. 8, are secured by rivets 4 to the under sides of the hopper floor sheets B and G, and extend downwardly in a vertical, transverse plane to a point considerably below the hinge rods of the door and are positioned closely adjacent the door flanges 1, so that they serve as baffles as the doors are being opened, to prevent the material from falling over the edges of the doors. These plates H are of arcuate formation at their edges, and the arc of curvature is determined by the front door braces F'. These braces extend outwardly beyond the plates H and move in arcs with the movement of the doors, and the plates are made as long as consistent with clearance for movement of these door braces. The plates are extended below sufficient to be cooperative with the door flanges when the doors are in open position so as to form and walls or baffles in the full open position of the doors.

In the center of the car beneath the center sills are ballast spreading plates J which serve to deflect and spread the top of the ballast pile between the rails. These plates lie in the same plane as the baffle plates H on each side thereof, and they are joined together with the baffle plates H to form a transverse strengthening member. The baffle plates H, as will be noted more clearly in Figs. 4 and 5, have end portions H' at their upper edges, which overlie the spreader plates J and are riveted or welded thereto.

The spreader plates are joined to the center sills by means of angle members J' which are riveted or otherwise secured to the plates and extend up into the center sill to which they are also secured.

In addition to the baffle and spreader plates, there is also provided transverse diaphragm and bearing support plates K. These plates K are disposed immediately adjacent and outwardly of the baffle and spreader plates, and in substantially parallel relation therewith. They are flanged at K' at their top portions and are secured by rivets or otherwise to the underfaces of the sloping hopper floor plates B and G. These transverse plates K provide rigidity and transverse strength to the car members, and they also serve as mountings for carrying a part of the door operating mechanism. The sheave wheels 5 which carry the door operating chains are positioned between the plates K and the baffle and spreader plates H and J. These sheaves are rotatable on the shafts 6 which have bearings 7 in the plates K and the baffle and spreader plates. The center doors are operated in pairs from jointed handles 12 located at points adjacent either side of the car. These handles are mounted on transverse

shafts 13 which extend from side to side of the car just beneath the center sills and are mounted in suitable end bearings 13' provided for that purpose. The shafts 13 carry worms 14 which mesh with and drive gear wheels 15, both the worms and gear wheels of each pair being suitably closed in a housing 16. The gear wheel of each set is attached to and drives the longitudinally disposed shaft 17 which is located centrally below the center sills of the car and which has a suitable bearing at one end in the casting 22 which is mounted on the downwardly extending hanger plate L, the plate L being attached to and supported by the center sill. The other end of the shaft 17 has a bearing in the housing 16 which encloses the worm and gear wheel. Between the spreader plates J and the transverse plate K at the ends of the hopper, the shaft 17 carries winding drums 18 upon which the winding chains 19 and 20 wind in opposite directions when the shaft is rotated. These chains extend over idler sheaves 5 and are connected at their ends through the door brace extensions 4 through the housing and guide castings 21. Thus the rotating of the shaft 17 and winding drums winds the chains upon the drums and swings the center doors to closed position, and the rotation of the shaft in the opposite direction unwinds the chains and allows the center doors to open by virtue of the weight upon them.

The side doors are individually operated by winding drum and chain connections. As shown more clearly in Figs. 4, 5 and 7, longitudinally extending shafts 11 are disposed at the side of the car beneath the hoppers and mounted in suitable bearings therefor. These shafts carry worm and gear drive connections 9, mounted in suitable housings 10 and adapted to be operated by jointed handles 8 located conveniently for the operator. These shafts are provided with winding drums 10 for the winding chains 10' which extend directly to and which are attached to the door brace extensions 4 through the guide castings 21.

I claim:

In a railway hopper car for the transportation of granular materials and having car walls, center sills and sloping floor walls, the latter forming longitudinally extending hoppers arranged in pairs, one on each side of the center sills and having their longitudinal centers in vertical lines with the rails of the railway track, a sub-hopper below each of the said hoppers comprising a pair of hinged interengaging doors having upturned edge flanges and disposed in a V-shaped relation with each other when in closed position, transverse plates suspended from the hopper floors at the ends of the doors for supporting the doors and for forming baffles against overflow of the load from the ends of the doors when being moved from closed to open positions, a downward extension into the sub-hoppers of the two sloping floor walls at the longitudinal ends of the hoppers and above the said sub-hopper doors whereby the upturned edge flanges of the hinged doors may sandwich between the baffle plates and the downward extensions of the two sloping floor walls to prevent leakage of materials from the car.
